UNITED STATES PATENT OFFICE

ROBERT J. THOMPSON, OF PARIS, FRANCE

FOLD COLLAR

Application filed January 12, 1926. Serial No. 80,820.

The invention relates broadly to a turn-down collar, and more particularly to an improved means for permitting a free sliding movement of the cravat when adjusting the same in the collar.

Collars of this character usually comprise two members, the inner member being in the form of a neck-band provided with buttonholes to permit the collar to be suitably fastened to the shirt. The scarf or cravat is inserted between these members. Considerable difficulty has been heretofore experienced, however, in adjusting the scarf or cravat, because the tension or friction between the same and the two members causes the scarf or cravat to resist easy movement. Such resistance will often tear the scarf or cravat, or cause injury to the shirt. This difficulty is quite common, and to overcome it my invention has for one of its objects the provision of novel means serving to release the tension against the cravat, so that the cravat may freely slide in the collar.

A further object of my invention resides in the particular means employed for accomplishing the aforesaid result, this means comprising essentially a simple separation or a spreading action of the outer member at the rear thereof, and an overlapping fold to cover over, or practically conceal, the separation.

In order to apprise those skilled in the art how to construct and practice my invention, I shall now describe a convenient embodiment in connection with the accompanying drawings, forming a part hereof, in which:

Figure 1 is a perspective view of a turn-down collar embodying my invention;

Fig. 2 is an enlarged detail view of a portion of the collar spread flat, illustrating the manner in which the lower edge of the outer member is cut to permit a pivotal-like action of the outer members at the separation;

Fig. 3 is a detail view, looking at the lower edge of the collar where separated, to show the overlapping relation of the fold at the separation;

Fig. 4 is an alternative embodiment of my invention, which omits the overlapping fold and provides a relatively wide separation; and

Fig. 5 is another alternative embodiment showing several vertical separations in the rear of the outer member.

Any convenient style of turn-down collar may be used, and in the drawings the outer member or flap of the collar is indicated at 1 and the inner portion or neck-band is indicated at 2. The usual buttonholes are provided at the front and rear of the neck-band to secure the same to the shirt of the wearer.

In order to eliminate the friction on the cravat caused by the pressure of the outer member 1 against the neckband or inner member 2, when the collar is drawn into place and fastened to the shirt, by buttoning, the outer member 1 is formed in a manner permitting it to spread or give along that portion where the friction or pressure is normally the greatest, when the cravat is pulled through the collar. This is accomplished by providing an opening or separation 5 substantially opposite the rear buttonhole 6, so that in effect the outer member 1 is formed of two sections 7 and 8 having a relatively movable overlapping relation at this separation 5.

It is preferable to provide an overlapping fold 9 at the separation 5, so as to close off the same and give the collar a more finished appearance. Furthermore, the sections 7 and 8 of the outer member 1 are held together and appear as if made of a single piece of material. As shown in the drawings, fold 9 is formed as an extension of section 7, and is adapted to lie under the adjacent edge of section 8. The length of the extending fold 9 may be just sufficient to overlap the separation and lie under the other section without pulling therefrom in the event the sections 7 and 8 are normally spread while attached to the shirt.

Sections 7 and 8 may be sewed together at 11, which is the point where the outer member 1 folds over from the inner member 2. Hence, it will be observed that any spreading at the separation will result in the members pivoting and moving away from each other at the point 11. By such an arrangement, sufficient spreading, or increasing of the effective length of outer member 1, with reference to the inner member 2 so as to provide a greater space therebetween for the cravat, is permitted

without allowing the overlapping fold 9 to slip out of position from under the adjacent section 8.

To facilitate such movement of these sections at the point of separation, I prefer to curve the lower edges thereof, as indicated at 12, and also to curve the lower edge 13 of the fold 9. The upper edge 14 of fold 9 is also cut away slightly to facilitate free action of the fold while in position. It will be observed in Fig. 3 that the fold 9 may be turned in slightly at 15 to permit both sections to lie in practically the same plane through their length, and thereby eliminate any bulge at the separation as the result of the presence of an overlapping fold.

In the embodiment illustrated in Figs. 1 to 3 inclusive, an overlapping fold is provided where the outer member is separated, but in the modification illustrated in Fig. 4, there is provided an opening 16 of such a size as will permit each section or the portion of the outer member on each side of the opening to act substantially independent so as to be able to spread.

Fig. 5 illustrates an alternative form accomplishing practically the same results, there being provided, however, two openings 18 and 19, which are so spaced from the rear center of the collar as to allow a spreading movement to the parts 20 and 21. These openings or separations may be cut substantially vertical, as shown in Figs. 1 to 3, or they may be at an angle or of substantial width, as illustrated in Figs. 4 and 5.

In practice, I find that a collar, as shown herein, will permit a cravat to be drawn therethrough without the inconvenience heretofore experienced. The tension or resistance on the cravat is effectively relieved, as the outer member 1 is permitted to spread and not tightly bind against the cravat, as heretofore occurred.

45 It will be apparent to those skilled in the art that various modifications and arrangements of the details may be had without departing from the spirit and scope of the invention.

Having thus described my invention and
50 illustrated its use, what I claim as new and
desire to secure by Letters Patent is:

1. A collar of the type described, comprising an inner member which is continuous from end to end, the free ends thereof being located at the front of the collar, an outer member having a transverse separation therein at the back of the collar forming spaced ends of said outer member at said back, and means on one of the ends of said outer member extending therefrom and underlying the adjacent end portion thereof for releasing the tension thereof against a cravat to permit the same to slide between said members.

65 2. A collar of the type described, compris-

ing an inner member which is continuous from end to end, the free ends thereof being located at the front of the collar, an outer member having a transverse separation therein at the back of the collar forming spaced ends of said outer member at said back, and a flexible extension on one of the ends of said outer member extending therefrom and underlying the adjacent end portion thereof for releasing the tension thereof against a cravat to permit the same to slide between said members. 70 75

3. A collar of the type described, comprising an inner member which is continuous from end to end, the free ends thereof being located at the front of the collar, an outer member having a transverse separation therein at the back of the collar forming spaced ends of said outer member at said back, and a flexible extension on one of the ends of said outer member extending therefrom and underlying the adjacent end portion thereof for releasing the tension thereof against a cravat to permit the same to slide between said members, said flexible extension being curved upwardly to engage the joint between the inner and outer members at said back and being slidable relatively thereto. 80 85 90

In testimony whereof, I have hereunto signed my name. 95

ROBERT JOHN THOMPSON.
